Gardner Stewart

ATTORNEYS.

UNITED STATES PATENT OFFICE.

ADOLPH HAENICHEN, OF PATERSON, NEW JERSEY.

SHAFT-BEARING.

SPECIFICATION forming part of Letters Patent No. 664,946, dated January 1, 1901.

Application filed March 21, 1900. Serial No. 9,497. (No model.)

To all whom it may concern:

Be it known that I, ADOLPH HAENICHEN, a citizen of the United States, residing at corner of Broadway and Prospect street, in the city of Paterson, county of Passaic, and State of New Jersey, have invented certain new and useful Improvements in Shaft-Bearings; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

This invention relates to mountings for revoluble shafting, and it has reference particularly to mountings for the shafts of a spinning-machine substantially like that shown and described in my copending application for United States Letters Patent, filed February 29, 1900, Serial No. 3,083.

One object of the invention is to so mount a shaft of the nature above indicated that the production of friction will be reduced to the minimum and the bearing be as simple and durable as possible.

A further object of the invention is to construct and arrange the bearings for a vertical shaft such as that shown and described in my copending application for United States Letters Patent for a spinning-machine, filed January 29, 1900, Serial No. 3,083, that the shaft may with facility be removed when occasion requires.

A still further object of the invention is to so construct a bearing designed to counteract the tendency of a shaft toward longitudinal movement that the parts thereof may be self-adjusting, notwithstanding uneven wear or the fact that the shaft is not disposed perfectly perpendicular with reference to said bearing.

The invention consists in the improved mountings for revoluble shafting and in the combination and arrangement of the various parts thereof, substantially as will be herein-after pointed out and finally embodied in the clauses of the claim.

Referring to the accompanying drawings, Figure 1 is a view in side elevation of the end portion of a spinning-machine, showing

certain revoluble shafts and the mountings therefor. Fig. 2 is an enlarged view, in side elevation, of a vertical shaft and its mountings, the latter being shown partly in section. Fig. 3 is a view in front elevation of the upper mounting for said vertical shaft; and Fig. 4 is a view of a portion of a horizontal shaft and one of its mountings, the latter being partly shown in section.

In the accompanying drawings, *a* designates the frame of a spinning-machine, while *b* denotes spindles revolubly mounted in said spinning-machine and adapted to deliver thread onto bobbins which may be arranged in brackets *c* and are adapted to be driven by rollers *d*, mounted on horizontal shafts *e*, which are journaled in the frame. *f* denotes a vertical shaft carrying sheaves *g*, over which extend bears *h*, that bear against the whrils *i* of said spindles, so as to rotate the latter. *j* designates a system of gearing operatively connecting each shaft *e* with a worm *k* on said vertical shaft.

l and *m* are the pedestals for supporting the vertical shaft *f*. Each of these pedestals consists of a plate *n*, having a pair of alined vertical slots *o*, adapted to receive the bolts for securing the pedestals to the end upright of the frame *a*. Since the slots extend vertically in each plate, the pedestal is rendered vertically adjustable when the bolts are loosened. The pedestal *l*, which constitutes the step-bearing for said shaft, has a socket *p*, adapted to receive the lower end of the shaft *f*, and in the top surface of said pedestal is formed around the socket an annular channel *q*, in which are arranged antifriction-balls *r*. Upon the shaft *f* is secured a collar *s*, said collar being rigidly secured in position by means of a feather-and-key arrangement *t*. Between said collar and the pedestal and resting upon the balls *r* is a washer *u*. This washer is of glass-hard steel. By virtue of this provision a bearing of the maximum durability is produced.

The pedestal *m* is divided, one part *v* thereof constituting the bracket and having the slots *o* above described and the other part *w* being the upper socket or pedestal proper for the shaft. The two parts have pairs of projections *x*, which are penetrated by bolts *y*

for securing said parts together. The part *w* is provided with a socket *z*, the same as the socket *p* of the lower pedestal, with the exception that it is somewhat larger. In this 5 socket is arranged a cup-bushing or thimble 1, directly receiving the end of the shaft. This thimble is adapted to be properly set by a screw 2, mounted in the top of the pedestal and adapted to bear against the top of the 10 thimble.

By arranging the pedestals so as to be vertically adjustable the shaft *f* may be removed without entirely removing either pedestal from the frame and without appreciable longitudinal movement of the shaft. The sheaves 15 do not have to be loosened, as they would have to be if the shaft were removed longitudinally, for the reason that they project into more or less confined openings in the upper 20 right of the frame, as seen in Fig. 1.

3 designates a horizontal shaft that is journaled in plumber-blocks or pedestals 4, which are mounted upon a stand 5, that projects from the frame. Said shaft constitutes the 25 drive-shaft of the machine, and it carries a pulley 6, over which the driving-belt may pass. It is operatively connected with the shaft *f*, so as to drive the same through the medium of an intermeshing worm and worm- 30 wheel 7 and 8, respectively, the former being secured upon the shaft *f* and the latter upon the shaft 3.

Into each pedestal or plumber-block 4 for the shaft 3 is screwed an annular bushing 9, which is penetrated by the shaft 3, the adjacent 35 interior edges of said bushing and the plumber-block being chamfered off to form a ball-race 10, in which are arranged about the shaft antifriction-balls 11. Upon the 40 shaft and between and close to the plumber-blocks are secured collars 12. These collars are fixed adjustably by means of binding-screws 13. The face of each pedestal or plumber-block adjacent the adjoining collar 45 is provided with an annular ball-race 14, in which is arranged another set of antifriction-balls 15. Against each set of these balls is adapted to bear a glass-hard steel washer 16, corresponding to the washer *u*, said washer 50 being interposed between the pedestal and the collar and acting, when the collar is properly secured in place, to keep the balls in their groove. Each glass-hard washer 16 serves the same function as does the corresponding 55 washer *u* for the vertical shaft.

The reason for providing the collars 12 and the bearings disposed between them and the plumber-blocks grows out of the fact that the worm-and-worm-wheel connection between 60 the shafts *f* and 3 tends to impart a longitudinal thrust to said shaft 3, as indicated by the arrow in Fig. 4. Of course it depends upon the direction in which the machine is working as to whether the shaft *f* will tend 65 to be moved in the one or the other direction longitudinally.

In Fig. 2 I show a slight modification of my invention. Though this modification is shown as applied to the mountings for a vertical shaft, it is also applicable to the mountings 70 for horizontal shafts. In this modification instead of employing the ordinary plain or disk-like washer said washer constitutes substantially the segment of a sphere, the same, of course, having an opening through it for 75 the reception of the shaft. This device is indicated by the reference character 17 in the figure mentioned, having its flat surface resting upon the balls *r*, while the curved portion of its surface sits in a correspondingly-shaped recess 18, formed in the collar *s*. The edges of the opening 19 in this washer may be rounded off, so that the shaft cannot possibly interfere with the action of said washer. It will be observed that by virtue of this construction 80 whatever the position with reference to the pedestal *l* may be its bearings are always self-adjusting, so as to work perfectly true.

Since I usually secure the upper pedestal 90 to a cross-bar 20 of the upright, which has strengthening-flanges 21, between which the part *v* of said pedestal is bolted, it is in order that the shaft *f* may be readily removed notwithstanding the fact that the upper one of 95 these flanges and the worm 8 coact to prevent dismounting the shaft that I divide the upper pedestal. Said pedestal being made in two parts, upon removing the bolts securing them the shaft *f* may be lifted till the worm 100 and worm-wheel clear each other, and then it can be removed without interfering with any other parts.

Having thus fully described my invention, what I claim as new, and desire to secure by 105 Letters Patent, is—

1. The combination, with a frame, of a vertical shaft, pedestals disposed the one above the other, said lower pedestal being adjustably secured to the frame and receiving the 110 lower end of said shaft, a collar fixed on said shaft, a hardened washer penetrated by said shaft, a ball-race in the lower pedestal and surrounding the shaft, balls arranged in said ball-race, said washer being interposed between the collar and the balls, and said upper pedestal comprising a socket portion and a bracket portion having projections, and bolts penetrating said projections to secure 115 said socket and bracket portions together, said socket portion receiving the upper end of said shaft and said bracket portion being adjustably secured to the frame, substantially as described.

2. The combination of a revoluble vertical 120 shaft, pedestals disposed the one above the other and having sockets receiving the ends of said shaft, a frame, said pedestals being secured to said frame and being vertically adjustable thereon, a collar fixed on said shaft, a hardened washer penetrated by the shaft, a ball-race in the lower pedestal and sur- 125

rounding the shaft, balls arranged in said ball-race, said washer being interposed between the collar and the balls, a bushing arranged in the upper pedestal, the shaft being capped by said bushing, and a set-screw arranged in the pedestal and bearing against the bushing, substantially as described.

In testimony that I claim the foregoing I have hereunto set my hand this 8th day of March, 1900.

ADOLPH HAENICHEN.
